UNITED STATES PATENT OFFICE.

BARNET NEWLAND, OF NEW YORK, N. Y., ASSIGNOR TO INCANDESCENT SUPPLY COMPANY, OF NEW YORK, N. Y.

DESIGN FOR A COMMERCIAL UNIT FOR NITROGEN-LAMPS.

52,403.

Specification for Design. Patented Sept. 10, 1918.

Application filed February 9, 1918. Serial No. 216,380. Term of patent 3½ years.

To all whom it may concern:

Be it known that I, BARNET NEWLAND, a citizen of the United States, residing at New York, in the county of New York and State of New York, have invented a new, original, and ornamental Design for a Commercial Unit for Nitrogen-Lamps, of which the following is a specification, reference being had to the accompanying drawing, forming part thereof.

The figure is a perspective view of a commercial unit for nitrogen lamps showing my new design.

I claim:

The ornamental design for a commercial unit for nitrogen lamps as shown.

BARNET NEWLAND.
